(57) **CLAIM**

The ornamental design for an adjustable drawer, as shown and described.

DESCRIPTION

FIG. 1 illustrates a perspective view of the adjustable drawer;

FIG. 2 illustrates a front view of the adjustable drawer;

FIG. 3 illustrates a rear view of the adjustable drawer;

FIG. 4 illustrates a left side view of the adjustable drawer;

FIG. 5 illustrates a right side view of the adjustable drawer;

FIG. 6 illustrates a top view of the adjustable drawer; and,

FIG. 7 illustrates a bottom view of the adjustable drawer. The broken lines are included for the purpose of illustrating environmental structure and form no part of the claimed design.
